[57] CLAIM

The ornamental design for a wall mounted holder for an electric curling iron, curling brush or the like, substantially as shown.

DESCRIPTION

FIG. 1 is a front, top and left side perspective view of a wall mounted holder for an electric curling iron, curling brush or the like showing my new design;

FIG. 2 is a rear, top and right side perspective view thereof;

FIG. 3 is a top plan view thereof;

FIG. 4 is a bottom plan view thereof.
